UNITED STATES PATENT OFFICE

GEORGE H. DERRICK, DECEASED, LATE OF OAKLAND, CALIFORNIA, BY VICTORY A. DERRICK, EXECUTRIX, OF OAKLAND, CALIFORNIA, ASSIGNOR, BY MESNE ASSIGNMENTS, TO INSTOGRAPH, LTD., A CORPORATION

ELECTRIC SWITCH

Application filed March 19, 1928. Serial No. 262,902.

This invention relates to switches for making and breaking contact in an electric circuit.

The primary object of the invention is to construct a switch or contacting members so that the contacts of the circuit will be automatically wiped and thereby cleaned by the operation of the switch member in making and breaking contact.

The preferred embodiment of the invention is illustrated in the accompanying drawings which form a part of this application and in which:

Fig. 1 is a side elevation of the device showing the switch with the contacts in open position.

Fig. 2 is a side elevation of the structure showing the switch in closed position.

Fig. 3 is a top plan view of the device shown in Figs. 1 and 2.

For a more comprehensive and clearer understanding of the invention, reference will now be had to the reference characters of the drawings in which like reference characters indicate like parts throughout the several figures of the drawings. Reference character 1 indicates a base of any suitable kind by which the device may be supported. 2 is an electromagnet having wire 3 for energizing the magnet by a current of electricity thereby making and breaking the circuit through contacts 4 of the magnet and 5 of the switch member 6. Switch member 6 has current wire 7 attached thereto in any suitable manner as at 8. Standard 9 pivotally supports switch member 6 in any suitable manner as, for instance, pivotal connection 10 with standard 9 shown in Figs. 1 and 2. Spring 11 having its upper end attached to switch member 6 as at 12 and its lower end attached to base 1 as at 13 is for the purpose of rocking switch member 6 on its pivot 10 and thereby drawing contacting member 5 away from contacting member 4 of the electromagnet when the electromagnet is deenergized.

Switch member 6 is composed of two flexible strips 14 and 15 bent at an angle as shown at 16 intermediate the standard 9 and electromagnet 2 forming an expandible angle for lengthening the switch member or switch member 6 may be curved upwardly between the standard and the electromagnet, either of which constructions will impart to contacting member 5 a sliding or wiping movement over the face of contact 4 carried by the electromagnet 2 when the parts are snapped together by the straightening of the switch member 6 at the point of angle 16 or the straightening out of the curve in the switch intermediate the standard and the electromagnet, which sliding or wiping movement automatically wipes the faces of the contacting members keeping them clean.

Strip 14 is provided at its outer extremity with spacing member 5a which holds strips 14 and 15 in spaced relation. It will be readily understood that when the electromagnet 2 is energized it will draw contacting member 5 of strip 15 into contact with contact 4 of the electromagnet 2 thereby magnetizing strip 15 which will exert a magnetic force on strip 14 toward strip 15 which will cause a straightening of the angle 16 therein which straightening results in a wiping action of the contact member 4 of the electromagnet by the contact member 5 of the strip 15, which straightening will also cause a wiping movement of the spacing member 5a of strip 15 at the point of its contact therewith.

Having thus described the invention, what is claimed is:

1. A relay switch comprising a base, an electromagnet supported by the base, a spring controlled armature including contiguous strips of spring metal bent upwardly from the base intermediate their ends and a spacing member interposed between the ends of the strips.

2. A relay switch comprising an electromagnet, a standard spaced from the magnet,

an armature pivotally related to the standard, said armature including two spaced apart spring metal strips bent upwardly intermediate the ends, a contact carried by the 5 electromagnet and a contact carried by the strips.

In testimony whereof I affix my signature.

VICTORY A. DERRICK,
Executrix of the Last Will and Testament of
10 *George H. Derrick, Deceased.*
